United States Patent

Des. 237,024
Patented Oct. 7, 1975

237,024

CHAIR OR SIMILAR ARTICLE

Karl Dittert, Schwabisch Gmund, Germany, assignor to
Giroflex-Entwicklungs AG, Koblenz, Switzerland

Filed June 18, 1973, Ser. No. 371,293

Claims priority, application Switzerland Feb. 23, 1973

Term of patent 14 years

Int. Cl. D6—01

U.S. Cl. D6—31

FIG. 1 is a front view of my chair or similar article, incorporating my invention;

FIG. 2 is a side view of the chair or similar article depicted in FIG. 1, as viewed from the left side of FIG. 1, the opposite side being similar to the side shown;

FIG. 3 is a rear view of the chair or similar article depicted in FIG. 1; and

FIG. 4 is a perspective view of the chair or similar article depicted in FIG. 1.

I claim:

The ornamental design for a chair or similar article, as shown and described.
